(57) **CLAIM**

The ornamental design for privacy screen assembly, as shown and described.

DESCRIPTION

FIG. 1 is a perspective view of the privacy screen assembly embodying the new design;

FIG. 2 is a front view thereof;

FIG. 3 is a rear view thereof;

FIG. 4 is a right side view, the left side view being a mirror image thereof; and,

FIG. 5 is a top view thereof.

The portions shown in phantom lines in FIGS. 1-5 are shown for environmental purposes only and form no part of the claimed design.
